UNITED STATES PATENT OFFICE.

JOSEPH RENE AYOTTE, OF CHICAGO, ILLINOIS, ASSIGNOR TO RENE SQUEEGEE COMPANY, OF CHICAGO, ILLINOIS, A CORPORATION OF SOUTH DAKOTA.

WINDOW-CLEANER.

1,203,684.

Specification of Letters Patent. Patented Nov. 7, 1916.

Application filed December 17, 1915. Serial No. 67,414.

To all whom it may concern:

Be it known that I, JOSEPH RENE AYOTTE, a subject of the King of England, and a resident of Chicago, county of Cook, and State of Illinois, have invented certain new and useful Improvements in Window-Cleaners, of which the following is a specification.

The main objects of this invention are to provide an improved form of window cleaner arranged for permanent attachment to a window so as to be operated from the inside for removing water, snow or sleet from the outside of the glass; to provide improved supporting means for the squeegee and the operating handle whereby they may be conveniently attached at any point on the window sash; to provide an improved construction of the squeegee; to provide improved means for preventing excessive pressure to be exerted by the squeegee against the glass during the cleaning operation; and to provide a simple and inexpensive device of this kind which is capable of being conveniently mounted in any desired position on practically any window sash.

An illustrative embodiment of this invention is shown in the accompanying drawings, in which:

Figure 1 is a perspective view of a window showing the improved form of cleaner attached thereto, the full lines indicating the position of the squeegee in its elevated position preparatory to swinging it down wardly for cleaning the glass, the dotted outlines representing the squeegee in its normal position. Fig. 2 is an enlarged longitudinal sectional detail of the cleaner mounting. Fig. 3 is a reduced side view of the cleaner showing the parts in their respective positions during the cleaning operation. Fig. 4 is a similar view showing the relative positions of the parts when the squeegee is being shifted into its elevated position preparatory to cleaning the window. Fig. 5 is a reduced inside elevation of a window showing the arrangement of the supporting plate for mounting the cleaner in the upper left hand corner of the window. Fig. 6 is a similar view showing the arrangement of the plate for mounting the cleaner in the opposite corner. Fig. 7 is an inside elevation of a long narrow window showing how the plate is attached to the frame so as to permit the cleaner to be swung through 180

degrees. Fig. 8 is an enlarged detail of the shaft to which the squeegee and operating handle are attached. Fig. 9 is an enlarged sectional detail of the bearing. Fig. 10 is an enlarged sectional detail of the squeegee.

In the construction shown in the drawings, a bearing 1 is integrally supported on a transverse plate 2 by means of which it is attached to the window sash 3 so as to support a squeegee 4 in the desired position to be swung across the glass 5 for removing water, snow or sleet therefrom. The squeegee 4 and an operating handle 7 are connected to opposite ends of a shaft 6 which is rotatably and shiftably mounted in the bearing 1.

The shaft 6 has journals formed at its opposite ends which fit within the ends of the bearing 1. At one end the journal is in the form of a bushing 8 and at the other end is in the form of a hub 9 integral on the handle 7. This arrangement of the journals provides an annular space 10 between the shaft and bearing intermediate the hubs 8 and 9 wherein the spring 11 is housed and wherein a quantity of graphite or other lubricating material may be retained for lubricating the journals of said shaft. The spring 11 embraces the shaft 6 and bears against the journal 8 and an annular shoulder 12 for normally urging the shaft 6 to move the squeegee 4 out of contact with the glass 5. Apertures 13 are formed in the bearing 1 so as to permit the passage of air into and out of the annular space 10 and prevent the creation of pressure or vacuum as the shaft is shifted back and forth.

The operating handle 7 is secured to the shaft 6 by being screwed onto the end thereof, preferably by means of a left-handed thread, and is locked thereto by means of a nut 14 preferably having a right-handed thread. A pin 15, carried by the handle 7, is arranged to engage apertures 16 formed in the opposed face of the bearing 1 whereby the squeegee is normally locked either in a horizontal or vertical position as may be desired. This pin is of such a length that it will bear against the end of the bearing 1 and allow the squeegee to be shifted from one position to the other without coming into contact with the glass. This is of advantage for the reason that when the window is covered with snow or sleet,

the squeegee can be shifted from its normal vertical position into a horizontal position for cleaning the window without having it come into contact and sweep the glass on being moved into said horizontal position.

5 The squeegee 4 (Fig. 10) is herein shown to be formed of a pair of comparatively thin flexible strips 17, preferably rubber, spaced apart by a strip 18 and secured between a pair of angle plates 19, bound together by means of screws 20. This as a unit is then detachably connected to an arm 21 which is shown to be integral with the shaft 6. An annular shoulder 22 is formed on the shaft 6 inwardly of the arm 21 and is arranged so that the face 23 thereof is located inwardly of the parallel parts of the angle plates 19 so that it will contact with the end 24 of the bearing 1 and limit the axial movement of the shaft 6 and thereby prevent the metal of the squeegee from coming in contact with the glass and also prevent excessive pressing of the squeegee 4 against the glass 5.

10 The plate 2 is formed of angularly disposed parts 25 and 26 respectively arranged so that the plate may be secured to the window sash 3 at any one of the corners thereof by attachment to the abutting side bars so as to support the axis of the shaft 6 inwardly of the angle formed by the inner edges of the two side bars of the window sash. These parts are also so arranged that the part 26 may be cut off and the part 25 used to mount the cleaner in the middle of a long narrow sash, such as indicated in Fig. 7.

15

When mounted on the sash, the end 24 of the bearing extends through a hole 27 formed in the glass and has a ring 28 secured on the end thereof. Gaskets 29 and 30 of rubber or other soft material are interposed between the glass and the bearing 1 and the ring 28 so as to form a closed joint around the hole 27. The ring 28 and the gasket 30, against which it bears, are formed so that the face 31 of the end 24 protrudes slightly beyond said ring. Thus, when the squeegee is operated, the shoulder 22 on the arm 21 bears against the end 24 and the pressure is directly upon the plate 2 so that there is no strain placed upon the glass direct.

20 Where the cleaner is mounted on a window which is shiftable into and out of the frame, a felt or rubber collar 32 may be placed on the bearing 1 to serve as a buffer to prevent injury to the frame when the window is shifted thereinto.

The device shown is operated in the following manner: The operator grasps the handle 7 with one hand and pulls thereon to 25 retract the pin 15 from an aperture 16 so that the squeegee may be swung into a horizontal position as shown in Fig. 1. As soon as the shaft has been turned slightly so as

to prevent the pin 15 from reentering the aperture 16, the pull on the handle is released and the pin 15 bears on the opposed face of the bearing. This allows the squeegee to be swung into said horizontal position without bringing the rubber strip 17 into contact with the glass. Except for this arrangement of the pin the operator would have difficulty in swinging the squeegee into its elevated position without sweeping the glass on the up-stroke, and then on the return stroke the material collected on the up-stroke would smear the glass on said return movement. The squeegee is then urged against the glass and by means of the handle 7 swung downwardly across the window so as to remove whatever may be accumulated thereon, such as snow, rain or sleet. When the swinging movement is completed, the handle 7 is released and the spring 11 shifts the shaft 6 axially so as to move the squeegee 4 out of contact with the glass and cause the reengagement of the pin 15 with the aperture 16. The cleaner is thereupon locked in its normal position, and the water thereon is allowed to run down and drain off the bottom thereof.

25 Although but one specific embodiment of this invention has been herein shown and described, it will be understood that numerous details of the construction shown may be altered or omitted without departing from the spirit of this invention as defined by the following claims.

I claim:

1. A window cleaner, comprising a bearing, a shaft mounted therein so as to rotate and also shift axially, a squeegee carried by one end of said shaft, a journal on said one end of said shaft fitting within said bearing, a handle connected to the other end of said shaft, a hub on said handle fitting within said bearing so as to provide a journal for the other end of said shaft, said bearing having an annular space around said shaft intermediate said journals so as to provide for the retention of a lubricant, and a spring embracing said shaft intermediate said journals and normally urging said squeegee into a retracted position.

2. A window cleaner, comprising a bearing, a shaft mounted therein so as to rotate and also shift axially, a squeegee carried by one end of said shaft, a journal on said one end of said shaft fitting within said bearing, a handle connected to the other end of said shaft, a hub on said handle fitting within said bearing so as to provide a journal for the other end of said shaft, said bearing having an annular space around said shaft intermediate said journals so as to provide for the retention of a lubricant, and a spring embracing said shaft intermediate said journals and normally urging said squeegee into a retracted position, said bearing having an 125

aperture communicating with said annular space so as to allow for the admission or escape of air from said space when said shaft is shifted axially.

- 5 3. A window cleaner, comprising a bearing; a shaft journaled in said bearing and shiftable axially, a squeegee carried on one end of said shaft, a handle attached to the other end of said shaft for shifting said
- 10 shaft to move said squeegee into contact with the glass of the window on which said cleaner is mounted and swinging said squeegee to clean the same, and a spring normally urging said squeegee into a retracted position out of contact with the glass, and a pin on said handle, said bearing having a recess therein for receiving said pin and locking said squeegee in a certain angular position, said pin being arranged to coact with said bearing when released from said recess for permitting said squeegee to be held out of contact with the glass when it is swung from said certain position into position for cleaning the window.
- 15 4. A window cleaner, comprising a bearing, a shaft journaled in said bearing and 25 shiftable axially, a squeegee carried on one end of said shaft, a handle attached to the other end of said shaft for shifting said shaft to move said squeegee into contact with the glass of the window on which said cleaner is mounted and swinging said squeegee to clean the same, a spring normally urging said squeegee into a retracted position out of contact with the glass, and a pin on said handle, said bearing having a recess 30 therein for receiving said pin and locking said squeegee in a certain angular position, said pin being arranged to coact with said bearing when released from said recess for permitting said squeegee to be held out of contact with the glass when it is swung from said certain position into position for cleaning the window.
- 20

Signed at Chicago this 14th day of December, 1915.

JOSEPH RENÉ AYOTTE
